UNITED STATES PATENT OFFICE.

FELIX F. CHERRY, OF AURORA, NORTH CAROLINA.

HAME-HOOK.

SPECIFICATION forming part of Letters Patent No. 571,894, dated November 24, 1896.

Application filed February 5, 1896. Serial No. 578,111. (No model.)

To all whom it may concern:

Be it known that I, FELIX F. CHERRY, a citizen of the United States, residing at Aurora, in the county of Beaufort and State of North Carolina, have invented certain new and useful Improvements in Hame-Hooks; and I do hereby declare the following to be a full, clear, and exact description of the invention, such as will enable others skilled in the art to which it appertains to make and use the same.

My invention consists in the novel features hereinafter described, reference being had to the accompanying drawings, which illustrate one form in which I have contemplated embodying my invention, and said invention is fully disclosed in the following description and claims.

Referring to the said drawings, Figure 1 represents a portion of a hame and trace with my improved hame-hook applied thereto. Fig. 2 is a horizontal sectional view of the same. Fig. 3 is a view similar to Fig. 1, showing the position of the hook when the loop of the trace or tug is removed or inserted. Fig. 4 represents a similar view showing the position of the parts when the hook is applied to or removed from the hame.

In the drawings, A represents a portion of one of the hames provided, in this instance, with a fastening-bar or staple *a* in the usual manner.

My improved hame-hook consists of two slotted plates secured together by a connecting-bolt or rivet, which engages a slot in one of said plates. B represents one of said plates, which I will term the "main plate" or "hook-plate" to distinguish it from the other. The said main plate is provided at one end with a laterally-bent portion *b*, which forms a broad retaining-hook to engage the fastening-bar *a* of the hame, and adjacent to its other end the said plate is provided with an open slot *b'*, extending preferably from a point on its upper edge intermediate the ends of the plate downwardly and then horizontally toward the end of the plate, forming a hook portion *b*. B' represents the other plate, which I will designate the "locking-plate," which is provided adjacent to its center with a short slot *b*, through which passes a rivet or bolt *B*, which secures the two plates together, but per-

mits them to move with respect to each other. The locking-plate B' is provided at one end with a laterally-turned flange *b*, which, when the plates are in operative position, engages and overlies the retaining-hook *b*, formed on the plate B, as shown best in Fig. 2. The opposite end of said locking-plate is provided with an open locking-slot *b*, which begins at substantially the same point as the slot *b'* in plate B and extends downwardly farther than the slot *b'* and then extends upward above the said slot *b'*, as shown at *b*, forming a locking projection *b* between the end *b* of the slot *b* and its open end, as will be seen in the drawings.

When the plates B B' are parallel, as they are when in operative position, the locking projection *b* extends directly across the slot *b'* in the main or hook plate B, thereby preventing a link or loop of the trace, which is placed in engagement with the plates, from slipping out. In order to insert or remove the chain-link C (if a chain-trace is employed) or the loop of any desired form of trace, the rear end of the locking-plate B' is raised as far as the slot *b* will allow, as shown in Fig. 3, thereby removing the locking projection *b* from across the slot *b'* in plate B, when portions of the two slots *b'* and *b* will coincide, so as to allow the loop or chain-link of the trace to be inserted or removed. This, it is obvious, could never happen while the device was in active use. As soon as the link is inserted and the plates released they will assume the position shown in Fig. 1, the locking projection *b* dropping in front of the link or loop and preventing its accidental removal.

When it is desired to attach the hook to a hame, the locking-plate is rotated until it lies across the main plate, as shown in Fig. 4, when the retaining-hook can be readily made to engage the fastening-bar *a* of the hame. The locking-bar is then rotated on its pivot in the direction of the arrow, Fig. 4, until the flange *b* engages the retaining-hook *b* of the other plate, as shown in Fig. 2, the slot *b* allowing the locking-plate to make the necessary movements.

It will be understood that the hook will be attached to the hame before the link or loop of the trace is placed in engagement with the trace.

It will be seen that this hook is strong and durable and can be instantly attached to a hame. The attaching and detaching of the traces can also be effected quickly and easily by the use of my improved hook.

What I claim, and desire to secure by Letters Patent, is—

1. A hame-hook comprising two plates each provided with a curved open-ended slot, one 10 of said plates having a semicylindrical retaining-hook to engage the hame-iron, and the other plate having a flange extending at right angles to the plate, adapted to lie over said retaining-hook, substantially as described.

2. A hame-hook comprising two parts each having an open-ended slot and a curved portion communicating therewith forming a hook, said parts being pivotally mounted one 20 upon the other and provided with means for detachably securing them to a hame, substantially as described.

3. A hame-hook comprising among its members the main hook-plate having a retaining-hook adapted to engage the hame and a slotted portion forming a hook for engaging a part

connected with the trace and a locking-plate pivotally connected with said main plate, having a retaining-flange adapted to engage and overlie said retaining-hook and having a locking projection adapted to lie across the slot of said main plate when the parts are in operative position, substantially as described.

4. A hame-hook comprising among its members, a main hook-plate having at one end a retaining-hook for engaging a part connected with the hame, and at the other end a slot forming a hook for engaging the trace, and a locking-plate having a flange for engaging the said retaining-hook, a slot adapted to receive a part connected with the trace, and a locking projection adapted to extend across the slot of the said main plate, a connecting-bolt for pivotally uniting said plates, one of said plates having a slotted portion engaging said bolt, substantially as described.

In testimony whereof I affix my signature in presence of two witnesses.

FELIX F. CHERRY.
